UNITED STATES PATENT OFFICE.

AUGUSTE SCHEUCHZER, OF RENENS, SWITZERLAND, ASSIGNOR TO FERRODESHER-BEUSE SCHEUCHZER SOCIETE ANONYME, OF RENENS, SWITZERLAND.

MACHINE FOR REMOVING WEEDS FROM RAILWAY ROADBEDS.

Application filed April 28, 1921. Serial No. 465,272.

To all whom it may concern:

Be it known that I, AUGUSTE SCHEUCHZER, manufacturer, citizen of the Republic of Switzerland, residing at Renens, Canton de Vaud, Switzerland, have invented a new and useful Improvement in Machines for Removing Weeds from Railway Roadbeds; and I do hereby declare the following to be a full, clear, and exact description of the same.

My invention relates to a machine for removing weeds from railway road beds. This machine is provided, with knives which are drawn through the ballast by means of an auxiliary motor automatically set in motion by parts of the railway road bed. In machines already known, a pilot roller is provided, said pilot roller running on the bottom of the rail and coming against the locking nuts of the latter. In several cases, this device has however proven inefficient and the present invention has for its object to improve devices of this type.

In the machine according to my invention, the auxiliary motor for raising and lowering the knives is set in motion by means of members drawn through the bed and actuated by the ties or sleepers. Two forms of a machine according to my invention are represented in the annexed drawings, as descriptive but not restrictive examples.

Figure 1 is a fragmentary side elevation of a railway car or other vehicle showing the invention applied thereto.

Figs. 2 and 3 are diagrammatic views illustrating various positions of the guide lever.

Fig. 4 is a fragmentary side elevation of a modified form of the invention.

Fig. 5 is a fragmentary vertical sectional view taken on the line V—V of Figure 4.

In the first form represented, the knives 15 are movable around an axis 151 located upon a wheeled support or vehicle. They are driven in the ballast by means of a lever 51 pivoted at 52 and a member 152, the lever 51 being actuated by a rod 50 carried by a piston (not shown) moving in a cylinder (not shown), steam being alternately introduced on each side of the piston. The alternative straight movements of said piston cause the knives to be driven in the ballast and to be raised to inoperative position. The movements of the piston are controlled

by a desired type of slide valve (not shown).

By means of a rod *a* and an arm *a*¹, a lever *c* pivoted in the support at *c*¹ and a lever *b* also pivoted in the support at point *b*² may be actuated. The lower arm *b*¹ of the lever *b* is curved; it has partially the form of an arc and is engaged on its concave portion by an arm *d* carrying the pilot roller *e* pressed by a spring *d*¹. Said arm *d* is carried by a guide lever *f* pivoted at *f*¹; the arm *d* may move along the guide lever *f*, the latter being drawn by said arm *d* in its oscillatory motions. This lever *f* is connected with a tube 32 in which a spring is provided, which tends to hold in said tube a rod *g* connected with and adapted to actuate the slide valve above referred to.

When the machine is transported to the working place, it is possible, by moving the rod *a*, by means of a hand wheel (not shown), to turn the lever *c* clockwise. The slotted rod *h* connected with the lever *c* acts then on the extremity of the lever *f* to which it is loosely connected in order to raise the roller out from the ballast. The sleepers have then no effect on the pilot roller and the machine may roll at any speed whatever.

When the machine has reached the working place, the rod *a* is moved in the opposite direction. Incident to the movement of the rod *a*, the lever *c* is turned so as to remove the extremity of the slot in the rod *h* out of engagement with the lever *f* and the latter is then only under the influence of the lever *b* and of the spring *d*¹ which draw the extremity of the arm *d*. The pilot roller is introduced in the gravel by the arm *b*¹ of the lever *b* which tends to move the parts *d* and *f* to an upright position. Each time that said pilot roller comes against a sleeper, the arm *d*, with the lever *f* oscillates around the pivot *f*¹ of the lever *f*, thereby actuating the rod *g* and the slide valve connected therewith and causing steam to flow in the cylinder and to raise the knives 15. As soon as the sleeper has been passed, the spring 43 connecting the tube 32 to the support acts on the lever *f* in order to return the pilot roller to the ballast where it remains till it reaches the next sleeper. The return movement of the lever *f* and rod *g* effects such adjustment of the slide valve as will permit

steam to flow on the other side of the piston in order to drive the knives in the ballast.

As above stated, the arm b^1 of the lever b has partially the form of the arc of a circle.

- 5 The centre of curvature of said arm is not, however, at the pivotal axis f^1 of the lever f , so that when the latter turns, the upper roller of the arm d following the curve of the arm b' , causes the pilot roller to be moved 70
10 in the direction of the knives. The closer the arm b' is to the pivotal axis f' , the more pronounced the movement of the pilot roller will be. Figs. 2 and 3 illustrate equal height 75
15 of sleepers in both cases; the machine must therefore move forward on the whole length 80
20 D in order that the pilot roller leaves the sleeper when the arm b^1 has the position shown in Fig. 2. Said length is equal to D¹ when the lever is inclined as shown in
25 Fig. 3. The motion of the lever moreover causes the initial position of lever d to be altered. When arm b^1 is near point b^2 , arm d is nearly perpendicular. It results that 90
30 its effect on the slide valve is advanced.
25 By means of said device, the mechanism may be suitable for several widths of sleepers.

In the second form of execution, a pilot roller rolling in the gravel and actuated by the sleepers also acts on the steam distribution 95
35 in order to drive the knives in the ballast and to raise them up. The knives are shown by 15 and they are pivotally mounted for swinging movement in the same manner as shown in Fig. 1 and are actuated by a
40 rod 152. The roller e is pivoted at the extremity of the lever d ; the latter may oscillate around a bearing d^1 fixed in a sliding piece k which may be perpendicularly moved in a slide bar fixed to the mass, said sliding
45 piece being moved by means of a hand wheel k^1 to which it is connected by arms k^2 and k^3 and by a lever k^4 pivoted in the mass. The slide bar k carries a conducting 100
50 piece l on which rolls the upper roller of arm d . The latter may slide in the piece by which it is connected to the slide bar k and it is always pressed against said conducting piece by the spring m . The upper extremity 105
55 of the arm d is moreover guided in a curved slot in the arm m keyed on an intermediary axis. Another arm o , actuating the rod at the extremity of which the slide valve (not shown) is provided, and an arm p , are also connected with the above intermediary axis.
60 The arm p is always caused, by a strong spring q , to turn anticlockwise. The relative position of the arm n , that is to say of its slotted end and of the rotating point d^1 of the slide bar k , causes the lever d to be
65 more or less inclined with regard to the rails on which the machine rolls. When the roller e , which rolls in the ballast, comes against a sleeper, it oscillates around the pivot d^1 and causes the shaft r to turn, the motion of
70 65 the latter being transmitted to the slide valve

by the arm o . In order to fix the time where the knives are to leave the ballast or to be driven in the latter, the sliding piece k is raised or lowered by means of the hand wheel k^1 . When the sliding piece is lowered, the initial position of the upper extremity of arm d is altered, the latter sliding then in the slot provided in arm n . This arm d is disposed upright so that, when the machine is set in motion, it will sooner 75
70 reach the sleeper. Moreover, instead of coming in contact with the latter with a part near its lower extremity, the roller is caused to sink more down in the ballast so as to come in contact with the sleeper in the point 80
75 where its diameter is perpendicular to the longitudinal axis of the arm b , the lead being thus increased. Therefore, the more the roller is driven in the gravel, the longer is the time during which it remains on the 85
80 sleeper, that is to say during which it raises the knives out from the ballast. The lowering of the knives is thus retarded. It is therefore possible to submit the motion of the knives to the width of the sleepers. The 90
85 form of the conducting piece l is such as to take into consideration the position of the roller e preceding the knives 15, with regard to the direction of running of the machine. The raising up of the knives requires a certain travel of the slide valve and therefore a certain oscillation of the arm d around the bearing d^1 . The parts are adjusted in such a manner that the lifting of the knives is effected close to the sleeper, at 95
90 the same moment when the roller leaves the head edge of the sleeper; the roller must then roll on the flat part where it must be held, in spite of the moving forward of the 100
95 machine, till the knives have passed the 105
100 sleeper. This may be obtained by means of a projection l' provided on the conducting piece, by which the pilot roller is moved rearwardly, with reference to the direction 110
105 of travel of the machine, as soon as the 115
110 roller of arm d reaches said projection. The 115
110 pilot roller leaves therefore the sleeper only after the knives have passed said sleeper, so that it is impossible that the sleepers be 120
115 damaged. In the drawings, only one pilot 120
115 roller is represented; however two rollers will generally be provided, each of them rolling at a certain distance from the axis 125
120 of the road. Both pilot rollers may act on the slide valves independently one of the other so that in the curved parts of the line or when the rails are fixed on wood sleepers of irregular form, the first roller which comes against the sleeper cause the knives to raise up and the roller which remains on the sleeper holds them up.

In order to bring the machine on the working place, the device is put out of action by raising up the sliding piece k . As arm n is not moved, the upper extremity 130
125

of arm *d* is leaded in the hollow of arm *n* so that arm *b* is turned till it is horizontal.

I claim:

1. In a machine of the character described, 5 a wheel mounted support adapted to traverse railway tracks, a movable knife carried by said support, and tie engaging means actuating said knife whereby to lift the latter over a tie engaged by said means.
- 10 2. In a machine of the character described comprising a wheel mounted support adapted to traverse railway tracks, a knife carried by said support, motor actuated means for raising and lowering said knife, and tie engaging means controlling the motor driven means for automatically lifting the knife over the ties.
- 15 3. In a machine of the character described comprising a wheel mounted support adapted to traverse railway tracks, a knife carried by said support, motor actuated means for raising and lowering said knife, and tie engaging means controlling the motor driven means for automatically lifting the knife over the ties, said last mentioned means including a pivoted lever and a pilot roller arranged to engage the railway road bed.
- 20 4. In a machine of the character described comprising a wheel mounted support adapted to traverse railway tracks, a knife carried by said support, motor actuated means for raising and lowering said knife, and tie engaging means controlling the motor driven means for automatically lifting the knife over the ties, the last mentioned means including a lever pivoted to the support, a road bed engaging roller carried by said lever, and means for varying the angle of
- 25 40 5. In a machine of the character described comprising a wheel mounted support adapted to traverse railway tracks, a knife carried by said support, motor actuated means for raising and lowering said knife, and tie

engaging means controlling the motor driven means for automatically lifting the knife over the ties, the last mentioned means including a lever pivoted to the support provided with a road bed engaging terminal, means for varying the normal position of the lever with respect to the surface of the road bed, and means for adjusting the last mentioned means.

6. In a machine of the character described 55 comprising a wheel mounted support adapted to traverse railway tracks, a knife carried by said support, motor actuated means for raising and lowering said knife, and tie engaging means controlling the motor 60 driven means for automatically lifting the knife over the ties, the last mentioned means carrying a pivoted lever having a road bed engaging terminal, means for varying the position of the lever with respect to the 65 surface of the road bed, and means for varying the position of the last mentioned means whereby to so control the motor driven means as to maintain the knife in inoperative position incident to the travel 70 of the latter over ties of varying widths.

7. In a machine of the character described, 75 a wheel mounted support adapted to traverse railway tracks, a movable knife carried by said support, said knife being movable vertically to a position to avoid railway ties, and tie engaging means actuating said knife whereby to lift the latter from a tie engaged by said means, said tie engaging means moving independently and 80 in advance of the knife whereby to permit the latter to closely approach the tie prior to lifting thereof.

In testimony whereof, I have signed my name to this specification in the presence 85 of two subscribing witnesses.

AUGUSTE SCHEUCHZER.
